[57] CLAIM

The ornamental design for a combined packaging and
dispensing container for extrusible comestibles, as
shown.

DESCRIPTION

FIG. 1 is a perspective view of a combined packaging
and dispensing container for extrusible comestibles
showing my new design, the opposite side being the
same in appearance; and

FIG. 2 is a top plan view thereof.

The side opposite that seen on FIG. 1 is the same as the
side shown.
